DESIGN FOR A FUR JACKET

Omar Kiam, New York, N. Y.

Application January 27, 1941, Serial No. 98,443

Term of patent 3½ years

To all whom it may concern:

Be it known that I, Omar Kiam, a citizen of the United States, residing in New York city, in the county of New York and State of New York, have invented a new, original, and ornamental Design for Fur Jackets, of which the following is a specification, reference being had to the accompanying drawing, forming part thereof, in which—

The design is characterized by the combination on the specific fur jacket disclosed of the loose pouch pockets in association with the double tufts at the shoulders and the single tufts at the top of each back panel, as shown.

I claim:

The ornamental design for a fur jacket, as shown and described.

OMAR KIAM.
